US0D1064314S

(12) **United States Design Patent** (10) Patent No.: **US D1,064,314 S**
(45) Date of Patent: ** Feb. 25, 2025

(54) **MOLECULAR DIAGNOSTIC DEVICE**(71) Applicant: **Visby Medical, Inc.**, San Jose, CA (US)(72) Inventors: **Victor Briones**, Gilroy, CA (US); **Gregory C. Loney**, Los Altos, CA (US); **Shaunak Roy**, Sunnyvale, CA (US); **Fred Bould**, Menlo Park, CA (US); **Kwan Hon Anson Cheung**, San Francisco, CA (US); **Robert Nicholas Dean**, Seattle, WA (US); **Lora Dimitrova**, San Francisco, CA (US)(73) Assignee: **Visby Medical, Inc.**, San Jose, CA (US)(**) Term: **15 Years**(21) Appl. No.: **29/803,603**(22) Filed: **Aug. 13, 2021****Related U.S. Application Data**

(63) Continuation of application No. 29/803,567, filed on Aug. 13, 2021.

(57) **CLAIM**

The ornamental design for a molecular diagnostic device, as shown and described.

DESCRIPTION

FIG. 1 is a front perspective view of a molecular diagnostic device, showing our new design;

FIG. 2 is a left elevation view thereof;

FIG. 3 is a right elevation view thereof;

FIG. 4 is a rear elevation view thereof;

FIG. 5 is a front elevation view thereof; and,

FIG. 6 is a top plan view thereof.

The broken lines in the figures depict portions of the molecular diagnostic device that form no part of the claimed design.
